LIQUID CONTAINER AND HAND PUMP SPRAY UNIT

Stewart J. Ridenour, Raytown, and Asa Pickinpaugh,
Kansas City North, Mo., assignors to Cook Chemical
Company, Kansas City, Mo., a corporation of Missouri

Filed Feb. 13, 1961, Ser. No. 63,897

Term of patent 14 years

(Cl. D31—3)

FIG. 1 is a side perspective view of a liquid container and hand pump spray unit, showing our new design.

FIG. 2 is a front perspective view thereof.

FIG. 3 is a rear perspective view thereof; and

FIG. 4 is a top plan view thereof, the bottom being essentially plain.

We claim:

The ornamental design for a liquid container and hand pump spray unit, as shown and described.
